Claims priority, application Great Britain Feb. 17, 1955

13 Claims. (Cl. 235—91)

This invention relates to summarising or totalising machines which, when operated, give a running cumulative total of a plurality of addenda and in particular to machines which, when operated, give a plurality of running cumulative totals of a plurality of addenda.

Summarising or totalising machines of the type which give a plurality of cumulative totals are especially useful for listing a variety of items, for example for dispatch from stores, or for analysing debit notes.

The object of the present invention is to provide an improved summarising or totalising machine of the type indicated.

According to the present invention there is provided a summarising or totalising machine comprising a plurality of counting devices of the rotary type, which on unidirectional rotation of its recording shaft displays a running cumulative total and a displaceable member capable of displacement of varying lengths proportional to the size of the numbers comprising the addenda, each of the counting devices being provided with a clutch for coupling the recording shaft of its counting device to the displaceable member so that the recording shaft of each of the said counting devices is individually rotatable by movement of the displaceable member.

The displaceable member is preferably an endless flexible member such as a sprocket chain arranged to co-operate with a sprocket wheel secured on or coupleable to the recording shaft of the counting device. The displaceable member may also, for example, be in the form of a rack which may co-operate with a pinion secured on or coupleable to the recording shaft.

Although the active path of the displaceable member is preferably linear it may for some applications be desirable to make it circular. Thus the displaceable member may be in the form of a sprocket or gear wheel. In that case the counting devices may be situated at the periphery of the wheel.

Means may be provided for yieldably urging the displaceable member towards its starting position. In that case, the series of numbers corresponding to the addenda may, if desired, be marked directly on or on means secured to the displaceable member. In the case where the displaceable member is endless and is not intended to be returned to its starting position, the series of numbers should be marked on a fixed support adjacent the displaceable member.

The displaceable member may have attached to it actuating means provided with a plurality of equally spaced locators capable of being manually engaged, such as apertures, corresponding to the addendum numbers. A stylus or similar tool is then inserted in the locator corresponding to the desired addendum number and displaced until it meets a stop, thereby displacing the displaceable member through a length corresponding to the addendum number. In the case where the displaceable member is a chain, the stylus may be inserted directly into the desired chain link. In the case where the dis-

2

placeable member is a wheel, the actuating means may be similar to the actuating disc of a telephone dial.

The clutch is preferably such that it is not necessary to exercise a manual force on it throughout the whole period that it effects a coupling between the recording shaft of its counter and the displaceable member. If the clutch is of the type that is urged to its disengaged or uncoupled condition by means of a spring or the like, locking means are preferably provided for locking the clutch in its engaged condition. It may be desired to add the same addendum simultaneously to a number of counters. The locking means are, therefore, preferably so arranged that locking of any clutch in its engaged condition does not cause unlocking of another clutch already engaged.

Preferably means are provided for simultaneously disengaging all engaged clutches. These means are preferably operated on the displacement member reaching its final input position for each particular addendum. For example, in the case mentioned above, where a stylus-like member meets a stop when the displaceable member has reached its final input position, means may be provided adjacent to or associated with the stop (which stop also constitutes the common termination point of the displacement path of the stylus-like member) which means, on actuation by the stylus, cause disengagement of all engaged clutches.

A preferred embodiment according to the present invention will now be described with reference to the accompanying drawings in which

Fig. 1 shows a plan view of the machine;
 Fig. 2 shows a plan view of the machine with the cover removed;
 Fig. 3 shows a section on a line III—III of Fig. 2;
 Fig. 4 shows a section on a line IV—IV of Fig. 2;
 Fig. 5 shows a detail of the machine with a stylus prior to actuation of the decoupling mechanism;
 Fig. 6 shows a detail of the coupling mechanism.

The machine has a case with a base 1, side walls 2, 2', end walls 3, 3', and a lid 4. Each of a plurality of counters 5 is individually mounted on a support bar 6, one end of which is arranged to swivel about a pin 7 mounted in an extension 8 of the base. The other end of bar 6 has secured to it a rod 9, one end of which passes through the lid and carries a button 10. The other end of the rod 9 is provided with an arrow-shaped tip 11. The displaceable member is in the form of a chain 12 supported by two spaced apart sprockets wheels 13, 13'. The sprocket wheels 13, 13' are mounted on ball bearings secured to spindles 14, 14'. The spindles 14, 14' are supported in members 15, 15', secured to the base 1.

In addition to the apertures for the rods 9, the lid is provided with apertures 16 through which the windows of the counters can be viewed, and with a slot-like aperture 17 which permits access to the upper run of the chain 12. The numbers corresponding to the addendum numbers are marked on the lid adjacent to the aperture 17.

One of the pins 18 of the chain is longer than the width of the chain. Sprocket wheel 13' is spring biased by means of a spring 44 secured to member 15' and to sprocket wheel 13'. The arrangement is such that, referring to Fig. 3, the sprocket wheel 13' is resiliently urged to rotate clockwise. This causes the chain 12 to occupy a position of rest, which is also its starting position, when stop pin 18 abuts against support member 15. A support 19, which is an extension of side wall 2' situated below the upper run of the chain, acts as a support for the stylus. For the sake of clarity support 19 has been omitted from Figs. 2 and 3.

Each counter 5 is provided with a recording shaft 20 to which is secured a sprocket wheel 21. The arrangement is such that when the button 10 of a counter is

depressed, the counter is tilted about pin 7 and the sprocket wheel 21 engages the lower run of chain 12. Thus the sprocket wheel 21 and the pivotal mounting for the counter 5 act as a clutch. In one position of the counter 5, sprocket wheel 21 is in engagement with the chain so that movement of the chain causes a corresponding rotation of the recording shaft 20 of that counter, i.e. the "clutch" is engaged. In the other position of that counter, sprocket wheel 21 does not engage with chain 20, i.e. the "clutch" is disengaged.

In order to ensure that the sprocket wheel 21 rotates only when it is positively driven by the chain, and that when uncoupled the correct whole numeral is clearly visible, a locator is provided. This consists of a projection 45 on the underside of support 19. The projection 45 is so arranged that when counter 5 is in its normal position, the projection engages with the sprocket wheel 21 and locks it in position. When the counter is tilted downwards, the sprocket wheel 21 disengages from the projection 45. Should the sprocket wheel, after being rotated by the chain be a fraction out of its correct position, for example so that only three-quarters of the last numeral on the counter is fully visible, the projection 45 will, upon engagement with sprocket wheel 21, rotate that wheel through that small fraction so that the last numeral is fully visible.

A locking device is provided to retain coupled counters in their coupled position when pressure on the buttons is released. The locking device comprises the arrow-shaped tip 11 of rod 9 which constitutes the locking member, and a latch bar 22 mounted in bearings 23 which permit longitudinal displacement of the latch bar. The latch bar is provided (see Fig. 6) with a plurality of apertures 24, one for each rod 9, the length of the apertures being approximately one and three quarter times the maximum width of the arrow-shaped tip 11. Each aperture 24 is provided with a latch shutter plate 25 which is urged against a stop 26 by means of a spring 27. The latch bar 22 is urged towards sprocket 13' by means of a spring 28. The arrangement is such that when button 10 is depressed, the arrow-shaped tip 11 of its rod 9 passes through the aperture in the latch bar, displaces the latch shutter plate 25 which thereupon springs back into its normal position, thereby locking the arrow-shaped tip 11, and with it the counter in its tilted position, i.e. with the counter's sprocket wheel 21 coupled to the chain 12.

A lever 29 which is arranged to swivel about a pin 30 has its lower end connected to latch bar 22 while its upper end carries a release pin 31. Release pin 31 is disposed just below the chain 12, slightly in advance of the end of the slot-like aperture 17 which is reinforced by a stop-piece 32. The release pin 31 extends through a slot in the side wall 2' so that it can also be operated externally.

Assuming that it is desired to add an addendum to the third and fifth counters, the buttons of these counters are depressed thereby engaging their sprocket wheels 21 with the chain 12. The counters are maintained in the coupled state by means of the locking device. The stylus is then inserted in the link of the chain opposite the desired addendum number and is then, with its lower end in contact with the support 19, drawn downwards until it meets the stop-piece 32. The release pin 31 is, however, disposed in its path so that, just before the stylus meets the stop-piece 32, it displaces the release pin 31 thereby causing lever 29 to swivel counter-clockwise (see Fig. 3). The counter-clockwise rotation of lever 29 pushes the latch bar 22 against the force of spring 28 away from sprocket wheel 13', thereby releasing the locking member 11 of the third and fifth counters. It will be evident that, due to the fact that each aperture in the latch bar is provided with its own spring-loaded shutter plate, any of the counters can be coupled individually without any of the counters which have already been coupled becoming uncoupled. However, should this not be required, i.e. should it be desired to have only one counter coupled at

any one time or should the number of counters be so low that any desired counters can be coupled simultaneously, then there will be no need to provide each aperture 24 with its own latch plate. In that case, the arrow-shaped tips would be arranged to engage directly with latch bar 22.

The advantage of utilising a spring-loaded chain is as follows. Assume that a counter has been coupled but that, inadvertently, the stylus has slipped out of the chain 10 before it has reached the release pin 31. In that case the chain will fly back until the stop pin 18 again meets the support member 15. During its fly back the chain will rotate the sprocket wheels of any coupled counters by the same amount that they have previously been rotated in the opposite direction during faulty manipulation and no error will, therefore, appear. As the stylus has not actuated the release pin, the counters have not been uncoupled so that the buttons remain in their depressed position. This is noticed by the operator who then 15 merely repeats the addition he has intended to make.

Each counter is also provided in a known manner with a resetting shaft 33 which is so arranged that when it is rotated clockwise through not less than two revolutions to a predetermined position, the figures of the counter 25 visible through the window are returned to zero. The resetting shaft 33 is provided with a flange 34 and has secured to it a collar 35. A pinion 36 (which constitutes the reset wheel) having a flange 37 is arranged freely rotatably on the resetting shaft. Clutch means between 30 the collar 35 (and hence the resetting shaft 33) and the pinion 36 are provided in the form of a pin 38 on the end face of the collar and a corresponding recess in the end face of the pinion. The pinion and collar are normally maintained in contact by means of spring 39 situated between flange 34 and flange 37. A hook 40 fixed to the lid is arranged to engage the flange 37 of the pinion and is so shaped that when its counter is tilted about pin 7 due to its button 10 being depressed, the pinion is forced to the left against the action of spring 39 45 so that pin 38 comes out of engagement with the recess in pinion 36. Thus the resetting clutch is engaged when the clutch on the recording shaft is disengaged and vice versa. A rack 41 provided with a handle 42 is mounted displaceably in slides 43 with its far end abutting 50 a stop 44 when in its normal position. The arrangement is such that the pinion 36 engages the rack in both its positions, i.e. whether its counter is tilted or not. In order to reset the counters, the rack is pulled out through a distance corresponding to not less than two revolutions of the pinion 36—which produces no visible effect 55 on the counter—and is then returned to its normal position. When the rack has resumed its normal position, all the resetting shafts have been rotated through not less than two revolutions to their predetermined position, and the counters are all reset to zero. The number of revolutions of the resetting shaft required for zeroing 60 may be different for different types of counters.

Apart from urging the collar and pinion into engagement, the spring 39 operates to return the counter to its 60 normal position when the locking means are released. However, should it not be desired to use spring 39 for both these functions, a separate spring may be provided to return the counter to its normal position. This spring, may, for example, be situated between the base 1 and 65 the bottom of the counter 5 or support bar 6.

Should it be desired to subtract a number, the stylus is inserted in the required link, and pulled until it touches the stop member 32 without any of the buttons being depressed. With the stylus still in position, the button 70 of the desired counter is then depressed and the stylus is disengaged. The chain thereupon flies back until the pin 18 is stopped by the support member 15. During this return the sprocket wheel 21 is turned clockwise and 75 subtracts the required number. In order to release the

locking device, the part of the release pin 31 projecting beyond the side wall 2' is then operated by hand.

When a sprocket wheel 21 is turned anti-clockwise, see Fig. 3, corresponding to the addition of an addendum, no movement of the resetting shaft occurs. However, when the sprocket wheel 21 is turned clockwise, corresponding to a subtraction, or due to faulty operation when the chain flies back without the counter having been uncoupled, rotation of the resetting shaft does occur. If rotation of the resetting shaft were prevented, the internal reset mechanism of the counter would be disturbed. It is for this reason that the collar 35 is disengaged from the pinion 36 when the counter is coupled to the chain. However, as zeroing of the counter depends on the resetting shaft (after being rotated through no less than two revolutions) taking up a predetermined position, it is essential that pinion 36 and collar 35 cannot become engaged in any position relative to one another. It is for this reason that the resetting clutch, in addition to providing engagement and disengagement between the collar 35 (and hence the resetting shaft) and the pinion 36 (and hence the rack 41), is so arranged, that by virtue of the pin 38 and the recess in pinion 36, the coupling between the collar 35 and pinion 36 can occur only when these two are in a predetermined relative position.

It will be evident that if the number of counters is increased beyond a certain number, which depends upon the size of the counters, an unduly long machine will be required and manipulation will become cumbersome. In that case it is preferred to place a plurality of summarising machines of the type illustrated side by side. If desired their spindles 14' and their release pins 31 can be coupled together. Such an arrangement has the advantage that the operator can always utilise the same chain.

We claim:

1. A summarising or totalising machine comprising in combination a plurality of counting devices of the type having a recording shaft and a resetting shaft, a displaceable member capable of displacement of varying lengths proportional to the size of the numbers comprising the addenda, a plurality of coupling members, one for each counting device, for coupling the recording shaft of its counting device to the displaceable member, so that the recording shaft of each of the said counting devices is individually rotatable by movement of the displaceable member, a plurality of reset wheels, one for each counting device, and a plurality of reset clutches one for each counting device for coupling the resetting shaft of its counting device to its reset wheel, means for engaging the reset clutch when the recording shaft coupling member is disengaged and for disengaging the reset clutch when the recording shaft coupling member is engaged, the reset clutch being arranged so that coupling between the reset wheel and the reset shaft occurs only when the reset shaft and reset wheel are in a predetermined relative position, and a displaceable reset member which is in engagement with all the reset wheels.

2. A summarising or totalising machine comprising in combination a plurality of counting devices of the type having a recording shaft and a resetting shaft, a displaceable member capable of displacement of varying lengths proportional to the size of the numbers comprising the addenda, said displaceable member or an actuatable member connected to it being arranged for movement by a stylus-like member, a plurality of coupling members one for each counting device, for coupling the recording shaft of its counting device to the displaceable member so that the recording shaft of each of the said counting devices is individually rotatable by movement of the displaceable member, means for simultaneously disengaging all engaged coupling members, trip means situated at a point slightly in advance of the common termination point of the displacement path of the stylus-like member, said trip means forming part of the disengaging means and being movable by the stylus-like member through that small distance to cause the said disengagement, a plurality of reset wheels, one for each counting device, and a plurality of reset clutches one for each counting device, for coupling the resetting shaft of its counting device to its reset wheel, means for engaging the reset clutch when the sprocket wheel of its counting device is disengaged and for disengaging the reset clutch when the sprocket wheel of its counting device is engaged, the

the stylus-like member, said trip means forming part of the disengaging means and being movable by the stylus-like member through that small distance to cause the said disengagement, a plurality of reset wheels, one for each counting device, and a plurality of reset clutches one for each counting device, for coupling the resetting shaft of its counting device to its reset wheel, means for engaging the reset clutch when the recording shaft coupling member is disengaged and for disengaging the reset clutch when the recording shaft coupling member is engaged, the reset clutch being arranged so that coupling between the reset wheel and the reset shaft occurs only when the reset shaft and reset wheel are in a predetermined relative position, and a displaceable reset member which is in engagement with all the reset wheels.

3. A summarising or totalising machine comprising in combination a plurality of counting devices of the type having a recording shaft and a resetting shaft, an endless chain capable of displacement of varying lengths proportional to the size of the numbers comprising the addenda, said chain being arranged for movement by a stylus-like member, means for yieldably urging the endless chain towards its starting position, a plurality of coupling members, one for each counting device, for coupling the recording shaft of its counting device to the chain so that the recording shaft of each of the said counting devices is individually rotatable by movement of the chain, means for simultaneously disengaging all engaged coupling members, trip means situated at a point slightly in advance of the common termination point of the displacement path of the stylus-like member, said trip means forming part of the disengaging means and being movable by the stylus-like member through that small distance to cause the said disengagement, a plurality of reset wheels, one for each counting device, and a plurality of reset clutches one for each counting device, for coupling the resetting shaft of its counting device to its reset wheel, means for engaging the reset clutch when the recording shaft coupling member is disengaged and for disengaging the reset clutch when the recording shaft coupling member is engaged, the reset clutch being arranged so that coupling between the reset wheel and the reset shaft occurs only when the reset shaft and reset wheel are in a predetermined relative position, and a displaceable reset member which is in engagement with all the reset wheels.

4. A summarising or totalising machine comprising in combination a plurality of counting devices of the type having a recording shaft and a resetting shaft, an endless chain capable of displacement of varying lengths proportional to the size of the numbers comprising the addenda, the chain being arranged for movement by a stylus-like member, means for yieldably urging the chain towards its starting position, each of the said counting devices being pivotally mounted and having a sprocket wheel on its recording shaft, so that in one position of the counting device the sprocket wheel is engaged with the chain and in its other position is disengaged from the chain, means for yieldably urging each counting device so that its sprocket wheel is disengaged from the chain, means for locking each counting device when its sprocket wheel is engaged with the chain, means for simultaneously disengaging all engaged counting devices, trip means situated at a point slightly in advance of the common termination point of the displacement path of the stylus-like member, said trip means forming part of the disengaging means and being movable by the stylus-like member through that small distance to cause the said disengagement, a plurality of pinions, one for each counting device, and a plurality of reset clutches one for each counting device, for coupling the resetting shaft of its counting device to its pinion, means for engaging the reset clutch when the sprocket wheel of its counting device is disengaged and for disengaging the reset clutch when the sprocket wheel of its counting device is engaged,

reset clutch being arranged so that coupling between the pinion and the reset shaft occurs only when the reset shaft and pinion are in a predetermined relative position, and a rack which is in engagement with all the pinions.

5. A summarising or totalising machine comprising in combination a plurality of counting devices of the rotary type, each device having a recording shaft and displaying upon the unidirectional rotation of its recording shaft a running cumulative total, a displaceable member capable of displacement of varying lengths from a starting position proportional respectively to the magnitudes of the numbers comprising the addenda, a like plurality of coupling members for respectively coupling the recording shafts to the displaceable member during a displacement, so that each recording shaft is individually rotatable by displacement of the displaceable member, and trip means at a point adjacent the path of the displaceable member adapted to disengage the coupling members from the displaceable member when a displacement has been completed.

6. A summarising or totalising machine comprising in combination a plurality of counting devices of the rotary type, each device having a recording shaft and displaying upon the unidirectional rotation of its recording shaft a running cumulative total, a displaceable member capable of displacement of varying lengths from a starting position proportional respectively to the magnitudes of numbers comprising the addenda, said displaceable member being arranged for movement by a stylus-like member; a like plurality of coupling members for respectively coupling the recording shafts to the displaceable member during a displacement so that each recording shaft of each of the said counting devices is individually rotatable by displacement of the displaceable member; means for simultaneously disengaging all engaged coupling members; and trip means situated at a point adjacent the path of the displaceable member and actuatable by the stylus-like member to disengage the coupling members from the displaceable member when a displacement has been completed.

7. A summarising or totalising machine according to claim 6 in which said displaceable member comprises an endless chain, means being provided for yieldably urging said chain towards its starting position.

8. A summarising or totalising machine comprising in combination a plurality of counting devices of the rotary type, each device having a recording shaft and displaying upon the unidirectional rotation of its recording shaft, a running cumulative total, a displaceable member capable of displacement of varying lengths from a starting position proportional respectively to the magnitudes of numbers comprising the addenda, said displaceable member being arranged for movement by a stylus-like member; a like plurality of coupling members for respectively coupling the recording shafts to the displaceable member during a displacement so that each recording shaft is individually rotatable by displacement of the displaceable member, latch means retaining each engaged coupling member in engagement independently of any subsequent engagement of any other coupling member; means for simultaneously disengaging all engaged coupling members; and trip means situated at a point along the displacement path of the stylus-like member and actuatable by the stylus-like member to disengage the coupling members from the displaceable member when a displacement has been completed.

9. A summarising or totalising machine according to claim 8 in which said displaceable member comprises an endless chain.

10. A summarising or totalising machine according to claim 9, in which means are provided for yieldably urging the chain towards its starting position.

11. A summarising or totalising machine comprising in combination a plurality of counting devices of the rotary type, each device having a recording shaft and a

resetting shaft and displaying upon the unidirectional rotation of its recording shaft a cumulative total; a displaceable member capable of displacement of varying lengths from a starting position proportional respectively to the magnitudes of the numbers comprising the addenda; a like plurality of coupling members for respectively coupling the recording shafts to the displaceable member, so that each recording shaft is individually rotatable by displacement of the displaceable member, latch means retaining each engaged coupling member in engagement independently of any subsequent engagement of any other coupling member; a like plurality of reset wheels, one for each counting device, and a like plurality of reset clutches one for each counting device for coupling the resetting shafts to their respective reset wheels, means for engaging the reset clutch of a device when its coupling member is disengaged and for disengaging the reset clutch when its coupling member is engaged, the reset clutch being arranged so that coupling between the reset wheel and the reset shaft occurs only when the reset shaft and reset wheel are in a predetermined relative position; and a displaceable reset number which is in engagement with all the reset wheels.

12. A summarising or totalising machine comprising in combination a plurality of counting devices of the rotary type, each device having a recording shaft and a resetting shaft and displaying upon the unidirectional rotation of its recording shaft a cumulative total; a displaceable member capable of displacement of varying lengths from a starting position proportional respectively to the magnitudes of the numbers comprising the addenda, said displaceable member being arranged for movement by a stylus-like member; a like plurality of coupling members for respectively coupling the recording shafts to the displaceable member during a displacement so that each recording shaft is individually rotatable by displacement of the displaceable member; means for simultaneously disengaging all engaged coupling members; trip means situated at a point along the displacement path of the stylus-like member and operable by the stylus-like member to disengage the coupling members from the displaceable member when a displacement has been completed; a like plurality of reset wheels, one for each counting device, and a like plurality of resetting clutches, one for each counting device, for coupling the resetting shafts to their respective reset wheel; means for engaging the reset clutch of a device when its coupling member is disengaged and for disengaging the reset clutch when the coupling member is engaged, the reset clutch being arranged so that coupling between the reset wheel and the reset shaft occurs only when the reset shaft and reset wheel are in a predetermined relative position; and a displaceable reset member which is in engagement with all the reset wheels.

13. A summarising or totalising machine comprising in combination a plurality of counting devices of the rotary type, each device having a recording shaft and a resetting shaft and displaying upon the unidirectional rotation of its recording shaft a cumulative total; an endless chain capable of displacement of varying lengths proportional respectively to the magnitude of the numbers comprising the addenda, all displacements having a common termination point, said chain being arranged for movement by a stylus-like member; means for yieldably urging the endless chain towards its starting position; a like plurality of engageable coupling members for respectively coupling the recording shafts to the chain so that each recording shaft is individually rotatable by displacement of the chain, an engaged coupling member being retained in engagement independently of any subsequent engagement of any other coupling member; means for simultaneously disengaging all engaged coupling members; trip means situated at a point along the displacement path of the stylus-like member and a small distance from the common termination point, said trip

means forming part of disengaging means and being movable by the stylus-like member through said small distance to cause said disengagement; a plurality of reset wheels, one for each counting device, and a plurality of reset clutches, one for each counting device, for coupling the resetting shafts to their respective reset wheels, means for engaging the reset clutch of a device when its coupling member is disengaged and for disengaging the reset clutch when its coupling member is engaged, the reset clutch being arranged so that coupling between the reset wheel and the reset shaft occurs only when the reset shaft

and reset wheel are in a predetermined relative position, and a displaceable reset member which is in engagement with all the reset wheels.
